Primary Examiner — Darlington Ly(74) *Attorney, Agent, or Firm* — Marshall, Gerstein & Borun LLP(57) **CLAIM**

The ornamental design for a cycle suspension rebound knob, as shown and described.

DESCRIPTION

FIG. 1 is a top and front perspective view of a cycle suspension rebound knob showing our new design; FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the cycle suspension rebound knob that form no part of the claimed design.
